(57) **CLAIM**

The ornamental design for a buckle for bag, as shown and described.

DESCRIPTION

FIG. 1 is a front, top, and right-side perspective view of a buckle for bag, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 shown in FIG. 2; and,

(Continued)

FIG. 9 is a front, top, and right-side perspective exploded view of the buckle for bag of FIG. 1.

The dot-dash lines in FIG. 2 represent cross sectional view indica only and form no part of the claimed design. The broken lines in the drawings represent portions of the buckle for bag and form no part of the claimed design.

1 Claim, 4 Drawing Sheets
